**COOLING UNIT FOR ELECTRONIC EQUIPMENT
OR THE LIKE**

Peter L. Hack, San Carlos, and Jackson W. Kendall, Jr.,
Los Altos, Calif., assignors, by mesne assignments, to
Varian Associates, a corporation of California

Filed Mar. 9, 1964, Ser. No. 78,932

Term of patent 14 years

(Cl. D67—2)

Fig 1

Fig. 2Fig. 3

FIGURE 1 is a perspective view of a cooling unit for electronic equipment or the like, showing our new design; FIGURE 2 is a top view; and

FIGURE 3 is a view in side elevation.

The bottom and rear are substantially flat and unornamented as best indicated in FIGURES 2 and 3. The opposite side is identical to the side shown.

We claim:

The ornamental design for a cooling unit for electronic equipment or the like, as shown and described.
